ATTORNEY

UNITED STATES PATENT OFFICE.

LOUIS SCHMETZER, OF ROTHENBURG-ON-THE-TAUBER, BAVARIA, GERMANY.

CARRIAGE-TOP.

SPECIFICATION forming part of Letters Patent No. 276,288, dated April 24, 1883.

Application filed July 25, 1882. (No model.)

To all whom it may concern:

Be it known that I, LOUIS SCHMETZER, a subject of the King of Bavaria, residing at the city of Rothenburg-on-the-Tauber, in the 5 Kingdom of Bavaria, German Empire, have invented certain new and useful Improvements in Carriage-Tops, of which the following is a specification.

This invention relates to an improved construction of tops and canopies for children's carriages; and it consists of certain improvements in the construction of tops and canopies for children's carriages and their attachment to the carriage-bodies, as will hereinafter be 15 fully described.

In the accompanying drawings, Figure 1 represents a detail view of one of the stays of an improved detachable carriage-top. Fig. 2 is a side view of a detachable carriage-top, shown 20 attached to the body of a child's carriage; and Figs. 3 and 3^a show two forms of the hook for fastening the top to the body. Figs. 4, 5, and 6 are children's carriages with adjustable canopies.

25 Similar letters of reference indicate corresponding parts.

The first part of my invention consists of a detachable top, B, for children's and other carriages, in which the stays B' are made of two 30 wooden side strips, a a, and a lateral top strip, b, which strips are connected by strong spring corner-pieces d, of steel, as shown clearly in Fig. 1. These springs d are so arranged that when the top B is removed from the body A 35 of the carriage the ends of the stays are sprung inwardly. To apply them to the carriage they are spread apart, as indicated by the arrows in Fig. 1, and applied to the metallic supporting-plates f, attached to the sides of the carriage-body A. By constructing the stays of the carriage-top in this manner the warping of the stays, if they are of one piece, is avoided, and a top furnished which always retains its shape. The top B is secured to the body 40 A by means of hooks i, which are driven down into the body through the rim of the same, the outwardly-projecting ends of the side hooks i passing through holes in the side plates, f, while a third hook i, at the rear part of the 45 body, is applied to the lowermost stay of the top B, as shown in Fig. 2.

In place of using the rear hook i, (shown in Fig. 3,) a hook, i', which is applied to the lowermost stay of the carriage-top, may be used for connecting the top to the rear part of the 55 body A, as shown in Fig. 3^a.

If the top part is desired to be removed from the carriage, the stays B' are removed from the side hooks, together with the supporting-plates f, by pressing the side plates and the ends of 60 the stays in outward direction, and then moving the entire top backward, so as to release it from the rear hook i. The stays are pivoted in the usual manner to the supporting side plates, f, and exert a strain in inward direction upon the same, owing to the corner-springs employed in each stay, so that the supporting-plates are firmly pressed against the fixed side hooks i, and thus the top firmly secured to the carriage-body without being liable to get off except in the manner described. 70

The adjustable top can be applied to the front or rear end of the body, as desired. It may be exchanged for use with a canopy, B², the stays g of which are pivoted to the side 75 plates, f, and retained, like the stays of the removable top, by a spring-locking device, for which Letters Patent have been granted to me heretofore, dated December 27, 1881, and numbered 251,472. The upper ends of the stays g 80 are also applied to the canopy by plates f' and similar spring-locking devices, whereby the canopy may be adjusted at any desired angle of inclination, as shown in dotted lines in Fig. 4. The canopy is further provided with 85 a lambrequin, formed of a front portion, t, and a rear portion, r, which are both attached to the frame h of the canopy, the lambrequin being made of such length as to reach down to the body A. The fabric composing the front 90 and rear sections, t and r, of the lambrequin is provided with vertical strips h' of elastic material, to the lower end of which rings and tassels h² are applied, by which the extended lambrequin-sections are applied to hooks and 95 buttons h³ of the body A, as shown in Fig. 6. On releasing the rings h² from the buttons h³ the rubber strips h' draw up the lambrequin-sections and retain them in folded-up state along the frame h, as shown in Fig. 5. In this 100 manner the canopy may be changed to a closed top in a very simple and convenient manner,

and at the same time an ornamental appearance be imparted thereto.

Having thus described my invention, I claim as new and desire to secure by Letters Patent—

5 The combination, with the carriage-body A, having side and rear hooks, *i*, of a detachable top, B, the stays of which are formed of side strips, *a a*, a lateral top strip, *b*, and connecting spring corner-pieces *d*, and of supporting 10 side plates, *f*, to which the stays are pivotally connected, said side plates and the lowermost

stay of the top B being retained respectively by the side and rear hooks, *i*, substantially as specified.

In testimony whereof I have signed my name 15 to this specification in the presence of two subscribing witnesses.

LOUIS SCHMETZER.
